UNITED STATES PATENT OFFICE

GEORGE W. BARNES, OF KENOSHA, WISCONSIN, ASSIGNOR TO SIMMONS COMPANY, OF NEW YORK, N. Y., A CORPORATION OF DELAWARE

BED DAVENPORT

Application filed September 2, 1926. Serial No. 133,107.

This invention relates to bed davenport and more particularly to bed davenport of the back-rest type.

The objects of the invention are to provide a bed davenport in which the back-rest may be shifted to a position where it will serve as a part of a bed bottom, the shifting being accomplished with a minimum expenditure of effort; to provide means for automatically assuring proper positioning of the back-rest in either its bed position or back-rest position; to provide an article affording the maximum of comfort when used as a davenport or as a bed, and to provide an article of the class described in which the back-rest and the bed bottom section may be made of similar size and shape and of like parts, whereby a minimum number of parts are required and assembly of the article facilitated, thus substantially reducing the cost of manufacture.

Other objects are to provide a structure which is neat in appearance, comparatively light in weight, simple and rugged, and in general to provide an improved structure of the class described.

Other objects and advantages of the invention will become apparent when the following specification is considered in connection with the accompanying drawings wherein I have illustrated a selected embodiment of my invention and in which:

Fig. 1 is an end elevation showing my bed davenport in position for use as a davenport.

Fig. 2 is a transverse section showing my bed davenport arranged for use as a bed.

Fig. 3 is a side elevation looking at the right-hand side of Fig. 1, and

Fig. 4 is a perspective of a detail of construction.

Referring now to the drawings, I have indicated a supporting frame 10 comprising end frames 11 and 12 which are connected and rigidly supported in their co-operative position by means of side rails 13 and 14. The side rails 13 and 14 may be conveniently connected to the end frames by means of suitable brackets 15 having a notch in their upper edges adapted to receive a headed pin secured to and projecting from the vertical

flange of the side rail, as will be readily understood by those skilled in the art.

A bed bottom section indicated at 16 comprises a rectangular frame, preferably of angle iron, and includes side members 17 and 18 and end members 19 and 20 which are suitably secured together at their ends to form a rigid frame. Bed fabric of suitable type is secured to the rectangular frame 16 and in the present instance I have shown bed fabric indicated at 21 which is stretched between the end members 19 and 20 of the bed bottom.

The outer side of the bed bottom 16 is supported by means of a pair of depending legs 22 and 23 which are secured to the respective corners of the bed bottom frame. The lower ends of the legs are provided with casters or rollers 24 which engage the floor to facilitate movement of the bed bottom, as will be hereinafter explained. The inner side of the bed bottom 16 is slidably supported by the supporting frame, which frame is provided with a pair of transverse channel members 25-25 which are secured to the side rails 13 and 14. A pair of roller brackets 26-26 are secured to the side member 18 of the bed bottom and are provided with suitable rollers 27-27 which enter the respective channel members 25-25 and are adapted to roll on the lower horizontal flange thereof. It will be apparent that the bed bottom 16 may be slid outwardly from its position shown in Fig. 1 to the position as shown in Fig. 2.

A back-rest 28, preferably of the same general construction as the bed bottom 16, is provided and is hingedly or pivotally connected to the bed bottom by suitable means. In the present instance I prefer to effect connection of the back-rest and bed bottom at their adjacent edges by means of a pair of brackets, one secured to the back-rest and one to the bed bottom and preferably each comprising link members 29 and 30 which are secured together by riveting or other suitable means, as indicated at 31, and which are secured to the bed bottom or back-rest as indicated at 32 and 33 respectively. The links 29 each extend a short distance beyond the connection 31 with the short link 30 and are pivotally con-

nected at their ends as indicated at 34. The pivotal connection 34 preferably includes a roller 35 which projects outwardly from the brackets and which is seated in a track 36 secured to the corresponding end frame. The track 36 is preferably of channel construction so as to limit movement of the roller 35 in both an upward and a downward direction whereby upward movement of the inner end 10 of the bed bottom is prevented and part of the load which normally would be on the supporting rollers 27 is taken therefrom and carried by the roller 35. By this means I may safely use structure of lighter weight than 15 otherwise would be proper.

The back-rest 28 is thus partly supported by its connection with the bed bottom and by engagement of the roller 35 in the track 36. I further support the back-rest by means of 20 a bell crank lever 37 which is pivotally mounted on a portion of the supporting frame by means of a suitable bracket 38 as clearly shown in Fig. 4. The long or upwardly extending leg of the bell crank is pivotally connected at its upper end as indicated at 39 to the back-rest. The lower arm or inwardly extending arm is connected by means of a suitable tension spring 40 with a portion of the supporting frame as by means of a 25 depending bracket 41 as most clearly shown in Figs. 1 and 2. It will be understood that I prefer to connect the back-rest and the bed bottom at their opposite ends in the manner described above in connection with one end 30 and also that I prefer to provide the above described bell crank arrangement at both ends.

In changing the bed davenport from the davenport position shown in Fig. 1 to the bed 40 position shown in Fig. 2, the operation is as follows:—The operator pulls the bed bottom 16 outwardly which slides or rolls on the floor and on the channel track members 25—25 as above explained. Because of the pivotal 45 connection at 34 between the bed bottom and back-rest, the back-rest is caused to move forwardly with the bed bottom and swings about the pivotal mounting of the bell crank 37 on the supporting frame or bracket 38. As 50 the back-rest 28 swings as above described, it swings about the hinged or pivotal connection 34 with the bed bottom and also turns on its pivotal connection 39 with the end of the bell crank lever 37. It will be apparent to 55 those skilled in the art that sufficient forward or outward movement of the bed bottom section will cause the back-rest to assume a position substantially co-planar with the bed bottom as shown in Fig. 2. In order to more 60 firmly support the back-rest in this co-planar position I preferably provide the lower bracket 26 which is secured to the bed bottom with an outwardly extending shoulder or seat 42 on which the forward end of the back- 65 rest is adapted to be seated. The rear end of

the back-rest is adapted to be seated on a small supporting bracket 43 as best shown in Figs. 2 and 3, the bracket 43 being secured in place on the upper flange of the channel member 25.

The spring 40 which is connected between a stationary part of the supporting frame and the lower end of the bell crank lever 37 is effective to prevent sudden dropping of the back-rest into its bed position because, as the bell crank 37 swings on its pivotal mounting on the frame, the spring is stretched and acts as a counterbalance. The spring is preferably of such strength that it will not of itself cause the back-rest to return to its davenport 70 position but will prevent sudden placement or slamming into bed position, whereby durability of the article is greatly increased.

To return the structure to davenport position, the operator merely lifts on the outer edge of the back-rest so as to effect a reversal of the above described operation of converting the davenport to a bed. In this operation the spring 40 will obviously be effective 75 to offer material assistance to the operator 80 since the spring normally tends to swing the bell crank in the direction in which it must travel in bringing the back-rest from the bed position to the davenport position. Inward movement of the bed bottom is limited by engagement of the legs 22 and 23 with the side rail 13, suitable provision being made to permit the legs 22 and 23 to move inwardly so that their inner edges will engage the vertical flange of the side rail. The legs 22 and 23 and the outer edge of the bed section do 85 not, therefore, project outwardly an objectionable amount. Swinging of the back-rest 90 with the bell crank 37 about the pivotal connection of the bell crank with the supporting frame and turning movement of the back-rest about its pivotal connection with the upper end of the bell crank is limited because 95 of its connection with the bed bottom which, as above explained, is limited in inward 100 movement.

I prefer to provide the pivotal connection 34 between the bed bottom and the back-rest at a point spaced above the bed bottom a distance substantially the same as the thickness 115 of a mattress or cushion which it is desired to use for increasing the comfort qualities of the bed davenport. It will be readily understood that by bringing the pivotal connection up to the top of the mattress or cushion 120 that interference with the movement of the back-rest from one position to another, by the mattress or other bedding, is avoided. By making the back-rest and bed bottom of substantially the same size and construction, 125 I eliminate the necessity of a large number of parts and thereby facilitate manufacture and assembly, whereby the cost of construction is lowered.

I am aware that various changes in size, 130

proportion of parts, and construction, as well as arrangement, may be readily made without departing from the essence of the invention, and I, therefore, reserve the right to make such changes as fairly fall within the scope of the following claims, which should be construed as broadly as possible consistent with the state of the art.

I claim as my invention:

- 10 1. In a bed davenport, the combination of a supporting frame, a seat section mounted on said frame so as to be adjustable from normal seat position to extended bed position, a back rest section normally extending upwardly from said seat section and hinged thereto, whereby adjustment of said seat section from its normal position to its bed position incidentally effects adjustment of said back rest to bed position, an arm pivotally connecting a point at the rear of said frame, with a point intermediate of the height of said back rest, said arm serving to control the adjustment of said back rest, and spring means connected between said arm and said 25 frame, tending to swing said arm rearwardly on said frame and effective for such purpose through substantially the entire arc of movement of said arm, for counterbalancing the weight of said back rest during adjustment thereof.
2. In a bed davenport, the combination of a supporting frame, a seat section mounted on said frame so as to be adjustable from normal seat position to extended bed position, a back rest section normally extending upwardly from said seat section and hinged thereto, whereby adjustment of said seat section from its normal position to its bed position incidentally effects adjustment of said 35 back rest to bed position, a bell crank pivotally mounted on a rear portion of said frame and below said back rest, said bell crank having a long arm extending upwardly and pivotally connected at its upper end to a point intermediate of the height of said back rest, and a short arm extending forwardly beneath said seat section, and a tension spring directly connected between the outer end of said short arm and a front part of said 40 frame, said spring tending to swing said long arm rearwardly and being effective for such purpose through substantially the entire arc of movement of said arm, for counterbalancing the weight of said back rest during adjustment thereof.

GEORGE W. BARNES.
